UNITED STATES PATENT OFFICE.

PAUL MAIWURM, OF MANSFIELD, OHIO.

PUBLIC AMUSEMENT DEVICE.

1,409,227.

Specification of Letters Patent. Patented Mar. 14, 1922.

Application filed August 30, 1920. Serial No. 407,039.

To all whom it may concern:

Be it known that I, PAUL MAIWURM, a citizen of the United States, residing at Mansfield, in the county of Richland and 5 State of Ohio, have invented a new and useful Public Amusement Device, of which the following is a specification.

My invention relates to public amusement devices, and its object is primarily to provide means for such amusement by devices whereby the bombing of submarines and the like may be simulated in sport, and captures of such floating vessels may sportively be realized and rewarded. It consists of simulating a running stream of water, having toy submarines and other toy vessels or objects floating in said stream; an elevated platform on the margins of said stream with bridge or bridges thereover, and means for 10 dropping toy bombs, or other similar projectiles, from points above said stream, whereby said floating objects may be hit and captured by skillful manipulation of said projectiles, while passing underneath said 15 points; and it further consists of means for carrying and for directing the course of said projectiles at said elevated points, and for discharging and returning the same to normal position at pleasure of the operator, 20 all as hereinafter set forth and as stated in the appended claim.

My invention is illustrated by the accompanying drawings in which similar letters and figures of reference indicate like parts. 25 Referring thereto, Fig. 1 is a sectional plan view of my invention from a point directly above the same; Fig. 2 is a sectional side elevation of Fig. 1, and showing a central structure and projectile operative devices; and Fig. 3 is an enlarged view of said devices, detached.

In the drawings, A is an elevated platform for spectators, and S, stairs leading thereto. Said platform may be circular, elliptical or 30 other desired shape, conforming to the shape and direction of the running stream D, which is endless, and of a depth of water sufficient to float therein a plurality of floating vessels or objects which are made subject to attack from points somewhat higher than said platform A, as hereinafter stated.

B is an intermediate platform within the inner circumference of said running stream, and on a common level with the platform A.

Upon said inner platform may be con-

structed a ticket office C or structure of any desired form to accommodate the manager of the amusement devices, which are accessible from said inner platform by persons who may be admitted thereto. E E (Fig. 60 1) are bridges across said stream leading from the outer platform A to the inner platform B and the ticket office C. R R are railings constructed on both sides of said platform A and said stream D and bridges 65 E, to prevent persons from falling.

At a plurality of stations along said stream, at points some distance higher than said platforms, I construct horizontally across the channel of said stream railings 70 or tracks e e, and arrange conveyances a a so as to ride thereon upon trucks 6, each having a projection 1 whereby it may be manually driven along said railing. A drum 2 is mounted on each pair of trucks, and adapted to carry a cable 3 which extends therefrom over said trucks, its free end carrying a toy projectile or bombing missile b, suspended thereon so as to hang above said stream D. Said drum is manually operable by means of a handle 4 thereon, and may be instantly released by means of a ratchet 5, whereby the projectile will fall by gravity to a point below the water level of the stream. By means of the railing e and trucks mounted thereon, the position of said projectile suspended on said cable as aforesaid may be shifted laterally to any point on the track e, so as to place it immediately above a floating object d in 80 the stream below which the operator intends to strike by the falling of the projectile thereon as it floats along thereunder.

The projectile b is preferably weighted, and is so constructed as to fall vertically; 95 and is provided with a suitable spear head or similar means for piercing the floating object, and lifting it out of the water, as shown, b' d' Figs. 2 and 3. The securing of this result depends largely on the skill and 100 sight of the operator, and herein lies the chief source of amusement. Rewards may be given to successful operators, and varied according to the character of the floating object struck.

I do not limit myself to the particular form of structure shown, and construction may be varied to suit locations, without departing from the scope of my invention.

Having thus fully described my invention 110

in its present form, what I claim as new, and desire to secure by Letters Patent is—

An amusement device comprising in combination, a running stream of water; a platform at an elevation above said stream; a railing across said stream above the level of said platform; toy objects floating in said stream; a projectile suspended from a conveyance on said railing, and adapted to be moved therealong to a predetermined po-

sition thereon directly above a floating object; and means for releasing said projectile instanter, at pleasure of the operator, substantially as set forth.

In witness whereof, I have hereunto set my hand this 27th day of January, 1920.

PAUL MAIWURM.

In presence of—

BENJ. W. McCRAY,
CHARLES SMITH.
